BELT CENTERING DEVICE

Filed Aug. 10, 1943

UNITED STATES PATENT OFFICE

2,366,390

BELT-CENTERING DEVICE

Gordon F. Dodge, Columbus, Ohio, assignor to The Jeffrey Manufacturing Company, a corporation of Ohio

Application August 10, 1943, Serial No. 498,090

6 Claims. (Cl. 74—241)

This invention relates to a belt centering or automatic training device.

An object of the invention is to provide an improved automatic belt centering or training device particularly for the return run of a conveyor belt which is operable automatically for reverse directions of travel of the belt.

Other objects of the invention will appear hereinafter, the novel features and combinations being set forth in the appended claims.

In the accompanying drawing,

Fig. 1 is a transverse sectional view of a conveyor including the belt centering device of my invention;

Fig. 2 is a side elevational view of the conveyor of Fig. 1;

Fig. 3 is an enlarged side view of the belt centering device of my invention shown in its operating position;

Fig. 4 is a further enlarged end view of the device of my invention showing particularly the means for pivotally suspending said belt centering device on a horizontal axis, the parts being shown in a non-belt conveying position;

Fig. 5 is a view taken on the line 5—5 of Fig. 4, looking in the direction of the arrows, some of the associated parts being shown in dotted lines;

Fig. 6 is an enlarged sectional view taken on the line 6—6 of Fig. 1, looking in the direction of the arrows; and

Fig. 7 is an enlarged sectional view taken on the line 7—7 of Fig. 6, looking in the direction of the arrows.

Referring to the accompanying drawing, there is seen a conveyor including a main frame 10 formed of spaced channel members across the tops of which are spaced troughing idlers 11 which support the upper run of a conveyor belt 12. As illustrated, the lower run of the belt 12 is flat rather than being troughed and at intervals it is mounted upon a belt centering or training device 13 comprising my invention.

The belt centering device 13 includes a pair of spaced brackets 14, 14 which are of similar structure and which are bolted or otherwise attached to the bottom flanges of the channels of main frame 10. Each of the brackets 14 is in the form of a yoke with wings which provide for attachment to the frame member 10 by virtue of spaced bolts 15.

The bottom edge of each bracket 14 forms a narrow semi-knife edged bearing surface 16 along which is adapted to roll a short piece of pipe or cylinder 17 which is rigidly attached to and forms an effective pivotal member of an end bracket 18, there being two such end brackets 18 rigidly attached to the opposite ends of a pipe 19 which together with brackets 14 and pipes 17 may be considered as constituting the main frame of the belt centering device 13.

Each of the stationary brackets 14 is provided with a screw 20 which is threaded through the bottom flange of said bracket and is provided with a pointed nose 21 which extends loosely through a hole in the bottom of the pipe 17. As illustrated, the short pipe 17 is rigidly attached to the bracket 18 by a set screw 22, and brackets 18 are attached to main frame pipe 19 by a pair of set screws 23.

10 From the description so far given and from the illustration in the drawing it is evident that the main frame 17, 18, 19 may swing about a horizontal axis which is along the bottoms of the short pipes 17, and the pointed nose construction 5 of screw 20 provides for this swinging movement while the short pipes 17 roll on the bearing surface 16. This swinging movement may be in either of two reverse directions, that is, either clockwise or counter-clockwise, and in Fig. 3 of 15 the drawing I have illustrated the swinging movement in the maximum clockwise direction, this maximum movement in both directions being determinable by a pair of spaced stops 24, 24 formed on opposite sides of the opening in bracket 14 through which the short pipe 17 extends.

Adjacent its center an upstanding bracket 25 is rigidly attached to the main frame pipe 19. Since the base of the bracket 25 is a cylinder which surrounds said pipe 19 it is preferably rigidly attached thereto as by set screws or the like.

30 It may be stated that when the end brackets 18 are in the upright position, for example, as illustrated in Fig. 4 of the drawing, the bracket 25 will also be in the upright position as illustrated in Fig. 6 of the drawing.

At its top the bracket 25 includes a removable cap 26 which is removably attached by screws 27. The cap 26 is half of a generally cylindrical portion of the bracket 25, through which cylindrical portion there is a bore 28 through which a non-rotary shaft 29 provided with a non-rotary shaft housing 30 extends. The shaft 29 and housing 30 are preferably rigidly connected together and consequently in effect constitute a 40 single part and may be considered as a single shaft.

The shaft 29 and housing 30 are pivotally mounted about a generally upright axis by means of pivot pins 31, the inner ends of which are 45 threaded into the housing 30 and the outer ends of which are journaled in appropriate bores in the upper cylindrical portion of bracket 25.

The pins 31 are provided with central lubrication bores 32, and a communicating lubrication 50 bore 33 extends to a grease gun fitting 34 on the bracket 25. On opposite ends the shaft 29 is provided with a pair of independently rotatable idler rollers 35, 35 preferably mounted on spaced anti-friction roller bearings.

55 60 The shaft 29 and housing 30 constitute in effect

a swinging frame or support by which the idler rollers 35 are swingably mounted on the main frame 19 etc., about a generally upright axis, but, as hereinafter pointed out, in operation this axis will swing in a plane parallel with the direction of movement of the conveyor belt 12.

When the conveyor belt 12 is stationary, the axis of the pivot of swing pins 31 will be vertical and the parts will be in the positions illustrated in Figs. 2 and 4 of the drawing. That is, a transverse plane with respect to the longitudinal axis of the conveyor which passes through the axis of the main frame pipe 19 and the axis of the pins 31, will be vertical. If now the conveyor is placed in operation and the lower run of the belt 12 travels in the direction illustrated in Fig. 3 of the drawing, the main frame 19 will pivot about its horizontal axis and the cylinders 17 will roll on the bearing surfaces 16 until such cylinders 17 engage stops 24, whereupon the axis of the pins 31 will be inclined to the vertical in the direction of travel of the lower run of the belt 12.

The swing frame or support constituted by the shaft 29 and housing 30 will be free to swing about this inclined upright axis. As a consequence of this arrangement, the return run of the belt 12 in traveling over the rollers 35 will be automatically trained or centered since the action of a pair of idler rollers mounted on an inclined axis has an automatic guiding or training action, as is well understood in this art.

Furthermore, in the most complete embodiment of my invention, greater efficiency is realized by employing two rollers 35 instead of a single roller since this increases the sensitivity of the device. So long as the return run of the belt 12 is properly centered, the swinging frame including the shaft 29 and housing 30 will have its axis substantially at right angles to the direction of travel of said return run of belt 12. The swinging movement of this swinging frame 29, 30, is, of course, limited by the size of the opening 28, and in practice such swinging frame is preferably free to swing from 2 degrees to 5 degrees on either side of central or normal position.

It is obvious that if the direction of travel of the belt 12 is reversed, the belt centering device 13 will automatically swing to reverse position from that illustrated in Fig. 3 so that the axis of the pins 31 is now inclined to the other side of the transverse vertical plane and again the device operates to maintain said return run of the belt 12 in proper alignment.

It may be further pointed out that the horizontal pivot axis of the main frame 17, 18, 19 is at the centers of the pipes 17 and moves in a plane parallel with surfaces 16. Also the center of gravity of the device 13 is preferably substantially along this plane. As a consequence, in the absence of an operating force such as provided by the movement of belt 12, the device 13 will stay in any position to which it is adjusted. This feature aids in the ease of automatic reversability of the device 13 for reverse travel of the belt 12 since practically no work is involved in moving it.

While the device as illustrated is applied to the return run of a belt of a conveyor, it is obvious that it may be employed for the carrying run particularly if through the carrying run the belt is maintained flat rather than troughed.

Obviously those skilled in the art may make various improvements in the details and arrangement of parts without departing from the spirit and scope of the invention as defined by the claims hereto appended, and I therefore wish not

to be restricted to the precise construction herein disclosed.

Having thus described and shown an embodiment of my invention, what I desire to secure by Letters Patent of the United States is:

5 1. A belt centering device including a stationary frame, a main frame pivotally mounted on said stationary frame for pivotal movement about a horizontal axis, a swinging support swingably mounted at its center on said main frame about an upright axis which may swing to opposite sides of a vertical plane through the pivotal axis of said main frame, and separate rollers mounted on said swinging support on opposite sides of said upright axis.

10 2. A belt centering device including a stationary frame, a main frame pivotally mounted on said stationary frame for pivotal movement about a horizontal axis, a swinging support swingably mounted at its center on said main frame about an upright axis which may swing to opposite sides of a vertical plane through the pivotal axis of said main frame, and belt supporting roller means mounted on said swinging support.

15 3. A belt centering device including a stationary frame, a main frame pivotally mounted on said stationary frame for pivotal movement about a horizontal axis, a swinging support swingably mounted at its center on said main frame about an upright axis which may swing to opposite sides of a vertical plane through the pivotal axis of said main frame, and separate rollers mounted on said swinging support on opposite sides of said upright axis, the center of gravity of said main frame and parts carried thereby being substantially at the pivotal axis of said main frame.

20 4. A belt centering device including a stationary frame, a main frame pivotally mounted on said stationary frame for pivotal movement about a horizontal axis, a swinging support swingably mounted at its center on said main frame about an upright axis which may swing to opposite sides of a vertical plane through the pivotal axis of said main frame, and belt supporting roller means mounted on said swinging support, the center of gravity of said main frame and parts carried thereby being substantially at the pivotal axis of said main frame.

25 5. A belt aligning idler including stationary spaced brackets, a main frame extending between said brackets and mounted thereon for pivotal rolling movement, said main frame including spaced cylindrical bearing members adapted to roll on bearing surfaces on said spaced brackets and spaced oppositely positioned stops therefor on opposite sides of a bracket, a pivoted swinging support mounted on said main frame for swinging movement about a generally upright axis which axis swings with said main frame, and belt supporting roller means on said pivoted swinging support.

30 6. A belt aligning idler including stationary spaced brackets, a main frame extending between said brackets and mounted thereon for pivotal rolling movement, said main frame including spaced cylindrical bearing members adapted to roll on bearing surfaces on said spaced brackets, a pivoted swinging support mounted on said main frame for swinging movement about a generally upright axis which axis swings with said main frame, and belt supporting roller means on said pivoted swinging support.
